UNITED STATES PATENT OFFICE.

EDWIN D. CASSEL, OF NEWARK, OHIO.

RAILROAD-RAIL-ENGAGING DEVICE.

1,220,319.

Specification of Letters Patent. Patented Mar. 27, 1917.

Application filed May 4, 1916. Serial No. 95,293.

To all whom it may concern:

Be it known that I, EDWIN D. CASSEL, a citizen of the United States, residing at Newark, in the county of Licking and State of Ohio, have invented certain new and useful Improvements in Railroad-Rail-Engaging Devices, of which the following is a specification.

My invention relates to improvements in railroad rail engaging devices for spacing ties and for other purposes. The object of my invention is: First, to provide a rail-engaging block of novel, simple and efficient construction; secondly, to provide a novel bearing block associated with the rail engaging block; and, thirdly, to provide a pressure producing instrument in combination with the rail-engaging block and the bearing block, all constructed, associated and combined in a novel manner to produce novel and advantageous results. With these objects in view, my invention consists in the novel construction and combinations of parts hereinafter fully described and particularly claimed.

In the accompanying drawings, illustrating my invention:

Figure 1 is a plan view of a portion of a railroad structure, showing one form of embodiment of my invention as employed in straightening crooked ties.

Fig. 2 is a side view, enlarged, of the parts shown in Fig. 1.

Fig. 3 is a plan view partly in section, showing another form of embodiment of my invention employed in separating rails.

Fig. 4 is a plan view of a portion of a railroad rail having my rail-engaging block thereon and showing my bearing block on the rail-engaging block.

Fig. 5 is a side view of the parts shown in Fig. 4.

Fig. 6 is a section, on line 6-6 of Fig. 4.

Referring to the drawings, 2 designates a rail engaging block adapted to extend transversely over a railroad rail 3. The block 2 has an opening 4 therein to receive the rail head 5, and the block 2 has an arm 7 which extends outwardly from the block in a direction transversely of the rail 3, whereby when pressure is applied to the arm 7 in a direction longitudinally of the rail 3, the block 2 will be slightly canted in a horizontal direction, causing the side walls 5 of the opening 4 therein to engage and firmly grip the rail; and the greater the

pressure against the arm 7 the greater will be the gripping action of the block 2 upon the rail. The block 2 is provided with downwardly extending feet 8 which rest upon the rail base 9 on the respective sides of the rail web 10. These feet 8 extend outwardly longitudinally of the rail 3 beyond positions beneath the body of the block 2, as shown, and they bear upon the top of the rail base 9 and prevent the block 2 from being canted vertically when pressure is applied to the arm 7 to cause the block 2 to grip the rail 3, as previously explained. The respective sides of the upper portion 70 of the block 2 are provided with outwardly extending ribs or flanges 11 which form handles adapted to be grasped by the hand of a person, as the hand embraces the upper portion of the block 2 when placing the block upon or removing it from a rail.

The arm 7 of the rail-engaging block 2 is adapted to support a bearing block 12, the body of which is provided with a pair of flanges 13 which embrace the arm 7, one 80 flange 13 extending over the arm 7 and the other flange 13 extending under the arm 7. The body of the block 12 is provided with an abutment or bearing part 14 which extends between the flanges 13 and has a rounded 85 free outer end which is seated in a socket or bearing 15 formed in one side of the arm 7. The other side of the arm 7 has a similar socket 15 formed therein so that the bearing block 14 may be applied to either 90 side of the arm 7. The bearing block 12 has a face 16 which is adapted to be engaged by a part of a pressure producing instrument, and projecting outwardly from the face 16 is a pair of spaced flanges 17 between which the said part of the pressure-producing instrument is adapted to be received. The purpose of the flanges 17 is to prevent vertical displacement of the said part of the pressure-producing instrument. 100 The free ends of the flanges 17 are turned toward each other to engage the said part of the pressure-producing instrument and prevent it from being withdrawn from the bearing face 16 except in a direction parallel to the face 16 and the flanges 17; and the block 12 has a stop projection 18 located to limit the movement of the said part of the pressure-producing instrument after it has reached a position in proper relation to the 105 bearing block 12 when the said part is inserted between the flanges 17.

In Figs. 1 and 2 I have shown the pressure-producing member in the form of a jack 19, and I have shown my improved device operating as a tie spacer. In these figures the rail engaging block 2 is shown engaged with one of the rails 3, one end of the jack 19 is shown engaged with the bearing block 12, and the other end of the jack 19 is shown engaged with one of the crooked ties 20 to be moved back into its proper position parallel to the ties 21. The jack 19 comprises a main body 22, a bar 23 slidable in the body 22 and a hand operated lever 24 fulcrumed, at 25, in the body 22 and carrying two pawls 26 and 27 which are adapted to engage teeth on the bar 23 and move it outwardly from the body 22 when the lever 24 is moved back and forth on its fulcrum 25 in the usual manner common to well known jacks. The outer end of the bar 23 is provided with a head 35 which is inserted between the flanges 17 of the bearing block 12 and bears against its bearing face 16; and the heel end 28 of the jack body 19 is engaged with the tie 20 to be straightened. When the parts are placed in this position and the lever 24 is operated to move the body 22 away from the head 35 on the bar 23, the block 2 will firmly grip the rail 3 and the heel end 28 of the jack 19 will move the crooked tie 20 back to its straight position.

In Fig. 3 of the drawings I have shown a pressure-producing member 29 comprising a body 30 in the form of a turn buckle and having right and left hand screws 31 screwed into the respective ends thereof. The outer ends of the screws 31 are provided with suitable heads 32 which are inserted between the flanges 17 of two bearing blocks 12 which are carried by the arms 7 of two rail-engaging blocks 2, as shown. These blocks 2 are placed on the two sections of a rail 3 on the respective sides of a joint 33 therein for the purpose of separating the sections of the rail 3 at the joint 33 when the turn buckle 29 is operated to separate the screws 31. During this operation, a suitable bar is inserted into the openings 34 in the turn buckle 29 to turn it; and as it is turned to separate the screws 31, the flanges 17 engage the heads 32 and prevent the screws 31 from turning. As the screws 31 move apart, the blocks 2 are caused to grip and separate the two sections of the rail 3. This separation of rail sections at the joint therein becomes necessary at times owing to the creeping of the rail under certain conditions of the road bed and traffic.

I claim:

1. A rail-engaging block comprising a body portion adapted to extend transversely over a rail and having an opening therein to receive the rail head, and having an outwardly extending arm, and having feet

adapted to bear upon the rail base, whereby when pressure is applied to said arm in a direction longitudinally of the rail said body portion will be canted horizontally into gripping engagement with the rail, and the said feet will prevent vertical canting of the body portion.

2. A rail-engaging block comprising a body portion adapted to extend transversely over a rail and having an opening therein to receive the rail head, and having an outwardly extending arm, and having feet adapted to bear upon the rail base, said feet extending outwardly longitudinally of the rail beyond positions beneath said body portion, whereby when pressure is applied to said arm in a direction longitudinally of the rail said body portion will be canted horizontally into gripping engagement with the rail, and the said feet will prevent vertical canting of the body portion.

3. A rail-engaging block having an outwardly extending arm and adapted to grip a rail when pressure is applied to said arm longitudinally of the rail, said arm having a socket therein, and a bearing block removably supported on said arm and having an integral bearing part seated in said socket and removable therefrom with said bearing block when it is removed from said arm.

4. A rail-engaging block having an outwardly extending arm and adapted to grip a rail when pressure is applied to said arm longitudinally of the rail, said arm having a socket therein, and a bearing block having a pair of flanges embracing said arm and supporting the bearing block thereon and permitting it to be removed therefrom, said bearing block having an integral bearing part extending between its flanges and seated in said socket and removable therefrom with said bearing block when it is removed from said arm.

5. A rail-engaging block having an outwardly extending arm and adapted to grip a rail when pressure is applied to said arm longitudinally of the rail, and a bearing block supported on said arm and having a face adapted to be engaged by a pressure instrument, said bearing block having a pair of outwardly extending flanges adapted to receive a part of a pressure instrument between them.

6. A rail-engaging block having an outwardly extending arm and adapted to grip a rail when pressure is applied to said arm longitudinally of the rail, and a bearing block supported on said arm and having a face adapted to be engaged by a pressure instrument, said bearing block having a pair of outwardly extending flanges adapted to receive a part of a pressure instrument between them, and said bearing block having a stop projection adapted to limit the movement in one direction of said part of a pres-

sure instrument when placed between said flanges.

7. A rail-engaging block having an outwardly extending arm and adapted to grip 5 a rail when pressure is applied to said arm longitudinally of the rail, and a bearing block supported on said arm and having a face adapted to be engaged by a pressure instrument, said bearing block having a pair 10 of outwardly extending flanges adapted to receive a part of the pressure instrument between them, and said flanges having their free ends turned toward each other to prevent movement away from said face of a 15 part of a pressure instrument placed between the flanges.

8. A bearing block having a pair of flanges extending from one side thereof and

adapted to embrace a part to be acted upon by the block, and having a pair of flanges 20 extending from another side thereof and adapted to embrace a part to act upon the block.

9. A rail-engaging block having an outwardly extending arm and adapted to grip 25 a rail when pressure is applied to said arm longitudinally of the rail, an adjustable bearing block supported on said arm, and a pressure producing instrument having one end engaging said bearing block and having 30 its other end provided with means adapted to engage a railroad structure.

In testimony whereof I affix my signature hereto.

EDWIN D. CASSEL.
